UNITED STATES PATENT OFFICE.

JAMES POWERS, OF NEW YORK, N. Y., ASSIGNOR TO POWERS ACCOUNTING MACHINE COMPANY, OF NEW YORK, N. Y., A CORPORATION OF DELAWARE.

HAMMER-LOCK FOR TABULATING MECHANISM.

1,234,385.

Specification of Letters Patent. Patented July 24, 1917.

Application filed September 17, 1915. Serial No. 51,127.

To all whom it may concern:

Be it known that I, JAMES POWERS, a citizen of the United States, residing in New York, in the county of New York and State 5 of New York, have invented certain new and useful Improvements in Hammer-Locks for Tabulating Mechanisms, of which the following is a specification.

This invention relates to perforated card 10 accounting machines, and particularly to anchoring means for locking the hammers of the tabulating mechanisms of such card accounting machines.

The main object of the invention is to 15 provide means for locking the hammers of tabulating mechanisms for card accounting machines so that when certain rows of data are not to be printed, hammers corresponding thereto may be locked to prevent corresponding type to be printed.

A further object of the invention is to provide means whereby to prevent the printing of certain rows of data and yet permit the cumulating of the amounts of such data.

Still other objects of the invention are to 25 provide a means which can be manufactured at low cost, is simple in construction, can be equipped on the tabulating mechanism of the type illustrated in my copending application Serial No. 802,362, filed Nov. 22, 1913, 30 without reconstruction, and to provide a means which can be quickly attached and removed from the tabulating mechanism.

These and other features, capabilities and 35 advantages will more fully appear from the subjoined detail description of one specific embodiment thereof, in which—

Figure 1 is a fragmental plan view of a tabulating mechanism equipped with the device forming the present improvement.

Fig. 2 is a side elevation, parts being broken away, and partly in section, showing a tabulating mechanism equipped with the device forming the present improvement.

Fig. 3 is a rear elevation of a tabulating mechanism showing the position of the device forming the present improvement.

Fig. 4 is an enlarged fragmental perspective showing the support of the present improvement on which hammer locks are secured.

Fig. 5 is a detached perspective showing one of the hammer locks.

In the present embodiment, there is provided a tabulating mechanism A equipped

with a plurality of hammers 12 pivotally mounted on the shaft 13, which hammers as illustrated in my copending application Serial No. 802,362, filed Nov. 22, 1913, are released with the actuation of type-carrying 60 sectors, a portion of one sector 14 being illustrated in Fig. 2.

The hammers 12 each have a head 15. The hammers 12 may be obstructed in their path of movement by hammer locks 16. The 65 hammer locks 16 are preferably disposed in the path of movement of the hammers 12 before the hammers 12 acquire their full momentum, that is immediately after having been released. For this purpose, the frame 70 17 of the tabulating mechanism A is provided with an extension 18 immediately in the rear of the heads 15 of the hammers 12 on which extension 18 there is formed a support 19 for the hammer locks 16. The support 19 comprises essentially two downwardly extending portions 20 which are secured to the extension 18 of the frame 17 and an upper portion 21 provided with a plurality of transversely extending slots 22 80 preferably divided into groups as shown in Fig. 3, each group in the present instance having eight slots, the slots to correspond with the groups of hammers 12 that may be equipped on the particular tabulating mechanism.

On the rear face of the upper portion 21 there is slidably mounted a hammer lock securing plate 23 which has its upper edge extending up above the bottoms of the slots 90 22. In the rear of the plate 23 there is provided a support 24 fastened to the frame 17, and on the rear face of the plate 23 there is provided a stop 25 spaced from said support 24 and to one side thereof, there being 95 a spring 26 connecting such stop 25 with the support 24 thereby normally drawing the plate 23 to one side. At each end of the plate 23 there is provided a slot 27. The slots 27 are parallel to one another and are 100 inclined relative to an imaginary line passing through the lower ends of the slots 22. Through these slots 27 locking screws 28 are passed and secured to the upper portion 21 of the support 19, on which the plate 23 105 is adapted to ride. At one end of the plate 23 there is provided a finger piece 29 by means of which the plate 23 is adapted to be drawn to one side against the tension of the spring 26, and due to the slots 27, the 110

plate 23 will be conducted in a downward direction so that its upper end will be disposed below the bottoms of the slots 22.

In these slots 22, the hammer locks 16 are adapted to be disposed, there being one hammer lock 16 for each slot 22, which hammer locks comprise essentially a piece of thin metal, such as sheet metal, having a finger piece 30 at its front end and a finger piece 31 at its rear end, the lower edge 32 of the sheet being substantially straight and being provided with a notch 33 near the finger piece 31. The notches 33 of the hammer locks 16 are all equally distanced from the rear finger pieces 31. For securing the hammer locks 16 in the slots 22 of the support 19, out of hammer locking position, the notches 33 will engage the upper edge of the securing plate 23. For anchoring the hammer locks 16 on the support 19, the plate 34 is provided which is fastened to the upper face of the upper portion 21 of the support 19 and extends between the finger pieces 30 and 31 of the hammer locks 16. In hammer locking position, the locks 16 are moved forwardly, as shown in Fig. 2, so that their front ends extend into the path of movement of the heads 15 of the hammers 12. When the notches 33 of the locks 16 are engaged by the securing plate 23, it will be necessary to first remove the plate 23 out of such notches before the hammer can be moved into locking position. This is done by grasping the finger piece 29 and moving the plate 35 23 to one side, the slots 27 in such movement drawing the plate 23 downward out of the notches 33. Thereupon, those hammer locks 16 desired to be moved, may be moved forward by manipulation of the finger pieces 30 or 31 or both, so that the edge 32 of the moved hammer lock will be disposed out of the path of movement of the plate 23, and then, upon the release of the plate 23, the spring 26 will return the plate 23 to normal. 45 position above the bottoms of the slots 22 and engage the notches 33 of those locks 16 which had not been moved forwardly. In the forward position or hammer locking position of the locks 16, as shown in Fig. 2, the 50 lower front ends of the locks 16 will be disposed in the paths of movement of the heads 15 of the hammers 12. The position of the hammers 12 in locking position is preferably such that it will obstruct the hammers 12 immediately after they are released and before they have acquired their full momentum.

It is obvious that various changes and modifications may be made to the details of construction without departing from the general spirit or scope of the present invention.

I claim:

1. In a tabulating mechanism having a plurality of hammers pivotally mounted, a

support, a plurality of plates forming hammer locks mounted on said support and adapted to be moved into the path of movement of said hammers to prevent their operation, and means for anchoring said plates either in hammer locking position or in idle position.

2. In a tabulating mechanism having a plurality of hammers pivotally mounted, a support, a plurality of plates forming hammer locks mounted on said support, there being notches on said plates, and a securing plate adapted to engage said notches when said plates are in idle position thereby to secure them in said idle position, the hammer locking plates being movable into the path of movement of said hammers to prevent their operation, the securing plate also coöperating with said hammer locking plates when in hammer locking position to anchor them in such position.

3. In a tabulating mechanism having a plurality of hammers pivotally mounted, a support, a plurality of plates forming hammer locks mounted on said support, there being notches on said plates, a securing plate adapted to engage said notches when said plates are in idle position, a spring for normally maintaining said plate in notch-engaging position, and means for guiding said securing plate out of notch-engaging position when said plate is actuated to release said hammer locks.

4. In a tabulating mechanism having a plurality of hammers pivotally mounted, a support, a plurality of plates forming hammer locks mounted on said support, there being notches on said plates, a securing plate adapted to engage said notches when said plates are in idle position, a spring for normally maintaining said plate in notch-engaging position, there being inclined slots in said securing plate, and means disposed on said support and passing through said slots so that when said securing plate is actuated to release said hammer locks it will be moved out of notch-engaging position.

5. In a tabulating mechanism having a plurality of hammers pivotally mounted, a support, a plurality of plates forming hammer locks mounted on said support, there being notches on said plates, a securing plate adapted to engage said notches when said plates are in idle position, a spring for normally maintaining said plate in notch-engaging position, there being inclined slots in said securing plate, means disposed on said support and passing through said slots, and a finger piece at one end of said securing plate by means of which said securing plate may be grasped when it is desired to actuate the same.

6. In a tabulating mechanism having a plurality of hammers pivotally mounted, a support, a plurality of plates forming ham-

- mer locks mounted on said support and adapted to be moved into the path of movement of said hammers to prevent their operation, an upwardly extending finger piece 5 at each end of a hammer lock, and an anchoring plate for anchoring said hammer locks on said support, said anchoring plate being secured to said support and extending between the finger pieces.
- 10 7. In a tabulating mechanism having a plurality of hammers pivotally mounted, a support, there being a plurality of slots in said support, and a plurality of plates forming hammer locks disposed in said slots and adapted to be moved into the path of movement of said hammers to prevent their operation.
- 15 8. In a tabulating mechanism having a plurality of hammers pivotally mounted, a support, there being a plurality of slots in said support, a plurality of plates forming hammer locks disposed in said slots and adapted to be moved into the path of move-
- ment of said hammers to prevent their operation, an upwardly extending finger piece 25 at each end of a hammer lock, and an anchoring plate for anchoring said hammer locks on said support, said anchoring plate being secured to said support and extending between the finger pieces. 30
9. In a tabulating mechanism having a plurality of hammers pivotally mounted, a support, there being a plurality of slots in said support, a plurality of plates forming hammer locks disposed in said slots and adapted to be moved into the path of movement of said hammers to prevent their operation, there being notches in said hammer locks, and a securing plate adapted to engage said latter notches when said hammer locks are in idle position thereby to secure them in such idle position. 35 40
